SALAD BOWL OR SIMILAR ARTICLE

Albert J. Dreitzer, New York, N.Y.

Application December 29, 1958, Serial No. 53,952

Term of patent 14 years

(Cl. D36—2)

Fig. 1 is an elevational view of a salad bowl or similar article, showing my new design;

Fig. 2 is a bottom view;

Fig. 3 is a fragmentary cross-sectional view along the line 3—3 of Fig. 1;

Fig. 4 is a fragmentary cross-sectional view along the line 4—4 of Fig. 2; and

Fig. 5 is a cross-sectional view along the line 5—5 of Fig. 1.

The characteristic feature of the design resides in a multi-pointed star on the base of the article, alternate points extending beyond the perimeter of the base and up the side walls of the article, said extensions being alternated with relatively wide and more rounded facets and being shorter in length than said facets.

I claim:

The ornamental design for a salad bowl or similar article, substantially as shown and described.
